UNITED STATES PATENT OFFICE

JAMES KEITH, OF LONDON, ENGLAND.

APPARATUS FOR PUMPING OR COMPRESSING GAS AND AIR.

SPECIFICATION forming part of Letters Patent No. 660,253, dated October 23, 1900.

Application filed January 12, 1899. Serial No. 701,954. (No model.)

To all whom it may concern:

Be it known that I, JAMES KEITH, of 27 Farringdon avenue, in the city of London, England, have invented certain new and useful 5 Improved Apparatus for Pumping or Compressing and Mixing Gas and Air, (which was patented in Great Britain on the 12th day of July, 1898, No. 15,291), of which the following is a specification.

10 This invention has for its objects to simplify and improve the construction of gas-compressing apparatus and to adapt it for compressing and mixing gas and air for illuminating and other purposes.

15 The invention is illustrated by the accompanying drawings, Figure 1 being a vertical section, Fig. 2 a plan of the improved compressor, and Fig. 3 a section, on a larger scale, of the motor employed to actuate the 20 pump. Figs. 3^a and 3^b are horizontal sections on lines *x x* and *y y*, respectively, of Fig. 3. Figs. 4, 5, and 6 show, respectively, a transverse vertical section, a longitudinal vertical section, and a plan view of the valve-box, the 25 valves being omitted to show their seats. Fig. 7 is a vertical section, and Fig. 8 a plan, of a modified form of apparatus in which gas and air are compressed and mixed; and Figs. 9, 10, and 11 are respectively a transverse verti-

30 cal section, a longitudinal vertical section, and a plan of the valve-box and valves employed in this modification, although it is evident that any suitable arrangement of non-return valves might be used instead of the form of 35 valve-box and valves shown. Fig. 12 is a side elevation showing the connections between the gas-bell and the motor, whereby the supply of water to the valve of the motor is controlled.

40 The improved apparatus illustrated by Figs. 1 to 6, in which gas only is compressed, comprises a double-acting pump which consists of a pump-cylinder A, provided with an annular water-space B, formed between the 45 pump-cylinder A and an inner open-ended cylinder C, secured upon the same sole-plate D as the pump-cylinder A. Into this water-space B a small gas-holder E dips, which holder constitutes the plunger of the pump, 50 the water acting as a seal when the plunger E is moved up and down by means of a water-motor of the construction hereinafter de-

scribed. The gas to be compressed is alternately drawn in and expelled both above and below the plunger E, the gas being drawn in 55 through pipes F G, which serve for outlets as well as inlets, communicating one, F, with the interior or lower side and the other, G, with the exterior or upper end of the plunger E, the other ends of each of these pipes being 60 connected to an inlet chamber or chambers H I in a valve-box J, connected to the gas-supply by an orifice J' and provided with valves H' I', adapted to open on the suction-stroke of the plunger E. A second set of valves H² 65 I² are provided, which are adapted to open on the expulsion-stroke of the plunger E and permit the gas previously drawn in to be forced by way of a delivery-chamber I³ and pipe K' (shown in dotted lines at Fig. 1) into 70 a gas-receiver K, which surrounds the pump portion of the apparatus. This receiver or regulator K, which is weighted at the bottom by means of a ring K'' to give the desired pressure to the gas or air contained within it, 75 dips into a water-space L, contained between the pump-cylinder A and an outer open-ended cylinder or casing M, provided with an overflow N, and is adapted to control a cock u on the water-supply pipe e' of the motor by 80 means of a rod S, connected at its upper end to receiver K at *x* and at its level end to the cock U, as shown at Fig. 12, and actuated by the rising and falling of the receiver.

The motor employed preferably consists, 85 as shown at Figs. 3, 3^a, and 3^b, of a piston a, connected to the pump-plunger E and working in a cylinder b, situated within the innermost cylinder C of the pump, a main valve c, composed of two pistons and operated by the 90 pressure-water, and an auxiliary valve d, composed of three pistons and adapted to be moved upward by the action of the lower end of the piston a upon a tappet at the upper end of the rod of the valve d and downward 95 by the exhaust-water from the under side of the piston a, these valves working in liners f² D', respectively, in a valve-casing f. The liner f² is provided with orifices f', which alternately admit the pressure-water to the 100 under side of the piston a and the exhaust-water therefrom, and the liner D', having ports d' d², which admit pressure-water to the under side of the main valve C and ports d³,

which, in conjunction with the ports d^2 , allow of the passage of exhaust-water therefrom according to the position of the pistons of the valve d . The pressure-water from the supply-pipe e' enters an orifice e in the auxiliary valve-casing f , where it acts constantly on the upper or smaller end of the main valve c , and from where it is taken by a pipe g to the upper side a' of the motor-piston a , on which it also constantly acts. The action of the motor and valves is as follows: Assuming the pump-plunger to be at the lowest point of its stroke and the auxiliary valve consequently at its lowest point and the main valve in its highest position, which latter valve until this instant, when the auxiliary valve d arrived in its lowest position, was receiving pressure-water from the orifice e by way of the passage e^2 (shown in dotted lines, Fig. 3) and ports d' and d^2 in the liner D' , in the position in which valves c d are shown the main valve c is just about to reverse, because the auxiliary valve d has established such connection between two series of ports d^2 d^3 in a liner D' in the valve-casing f that an opening to an exhaust-passage f^3 , leading into the innermost cylinder C , is allowed to the pressure-water to pass, as shown by the arrows, to said passage f^3 from behind the larger end c' of the main valve c and because the pressure-water, constantly acting on the smaller end c^2 of said valve, is now able to effect reversal. When this reversal of the main valve c to the lower end of its casing f has taken place, the pressure-water at the upper end c^2 is able to pass, as shown by the dotted arrows, by way of a series of ports f' in a liner f^2 in said casing f to the under side a^2 of the piston a , where it acts on a greater area than the pressure-water, constantly acting on the upper end of said piston, and so causes the motor-piston a to rise to the upper end of its stroke. As the motor-piston a nears the upper end of its stroke it acts on the nuts or tappet on the upper end of the rod of the auxiliary valve d and carries said valve upward (notwithstanding the action on the upper end of the valve d of the pressure-water) with it until the motor-piston comes to rest at the upper end of its stroke. The effect of so moving the auxiliary valve is to shut off communication between the ports d^2 and the ports d^3 and to establish communication, as shown by the dotted arrows, between the ports d^2 and a series of ports d' in the same liner, the latter ports communicating constantly by way of the pipe e^2 (shown in dotted lines at Fig. 3) with the supply-orifice e in the casing f . The pressure-water from the interior of the liner D' , admitted thereto from the pipe e^2 by the ports d' , now passes through the ports d^2 to the under side c' of the main valve c , when, acting on a greater area than the pressure-water constantly acting on the upper side of said valve, it forces it to the upper end of its stroke, thus cutting off connection between the pressure-water orifice e , the

ports f' in the liner f^2 , and the bottom a^2 of the motor-piston a and establishing communication by way of the ports f' and d^3 in the liners f^2 and D' , respectively, between the under side a^2 of the motor-piston a and the exhaust-passage f^3 , leading to the interior of the innermost cylinder C , whereupon the pressure-water, acting upon the upper side a' of the motor-piston a , causes said piston to return to its original position at the bottom of its cylinder, and the exhaust-water driven out by the descending piston acts to return the valve d also to its lowest position. This completes one cycle of operation, and during the upward stroke of the piston gas is drawn in through the pipe F to fill the space between the surface of the water and the inner surface of the plunger E , while at the same time the gas formerly drawn in through the pipe G and filling the space between the outer surface of the plunger E and the cylinder A is being expelled. At the next or downward stroke of the plunger E the under side of said plunger is expelling while the upper is sucking in gas.

In the modification of the invention illustrated by Figs. 7 to 11, in which the apparatus is designed to draw in a proportion of air with the gas and compress both for use, particularly in incandescent gas-lighting, an additional annular or double cylinder E' , open at its upper end, as shown particularly at Fig. 7, is provided, which is fixed to or forms part of the plunger E and dips into the water contained in the inner cylinder C , secured to the sole-plate D and referred to in the previous modification as the "inner" cylinder of the pumping apparatus. This annular cylinder E' is provided with a valve E^2 , which allows the water to enter the annular space on the downward stroke of the plunger, but prevents its returning on the upper stroke, the surplus water overflowing at the open end of the double cylinder E' over the top of the plunger E into the water seal B , formed between the inner and outer cylinders C A of the pump apparatus. Into this annular or double cylinder E' dips a cylinder A' , secured to and suspended from the cover of the outer cylinder A . These two cylinders E' A' form inner chambers, into the insides of which air is drawn, and into outer chambers formed between their outer peripheries and their adjacent cylinders gas is drawn at the same time, the gas and air being discharged from their respective chambers simultaneously and at the same pressure. The drawing in and discharging of air and gas are accomplished by the addition to the previously-described modifications of an air-valve box O , (particularly shown at Figs. 8 to 11,) having two separate pipes P Q , connecting to the top and bottom sides of the plunger E , and suction and delivery valves O^2 O^3 O^4 O^5 , as described with reference to Figs. 1 to 10, the delivery-chamber R of the air-valve box O being connected to the

delivery-chamber I^3 of the gas-valve box J by a passage O^7 , so that the air and gas mix regularly in fixed proportions.

In order to prevent any possible escape of gas through the air-inlet valves, which might happen should the valves leak when the apparatus is not working, the air-inlet O^6 to air-valve box O is connected to a water-seal valve S , which will effectually prevent any such leakage escaping to the outside. This water-seal valve S consists of a closed box, which is bolted to the side of the outermost cylinder or casing M and is provided with a pipe O^6 , open to the atmosphere. The waste water is carried down from the overflow N on the outer casing into the water-seal box by a pipe T and then overflows through a deep trap U . The air-inlet pipe O^6 dips about one-half inch into the water in this box S , which is of such capacity that in the case of back pressure through the air-valves the water will rise up both the air-inlet and overflow pipes O^6 T , respectively, considerably more than the height due to the working pressure of the gas before the water-level gets below the bottom of the air-inlet pipe O^6 . This arrangement of water-seal box S prevents the gas escaping through the trap U , so that in the event of the air-suction valves O^2 O^3 leaking back when the apparatus is not in motion the water simply rises in the pipes according to the pressure and also effectually washes the air, which is compelled to pass through the seal before reaching the air-valve box O , thus preventing dust collecting in the valves and other parts of the apparatus.

The mixed air and gas can either be taken for use direct from the delivery end of valve-box J or taken from the holder by a separate stand-pipe in order that they may be more thoroughly mixed.

The water-supply to the motor is controlled by the rising or falling of the gas-bell K by means of a rod S , connected at its upper end to the bell at x and at its lower end to a lever 45 T on a cock U in the supply-pipe e' .

Having now described the invention, what I claim, and desire to secure by Letters Patent, is—

1. A double-acting gas-compressing pump 50 comprising a cylinder, a pump-plunger moving therein having gas-pipes for the inlet and discharge of the gas to and from the upper and lower sides of the plunger, a loaded gas holder or receiver surrounding the pump 55 plunger and cylinder, a fluid-pressure motor for operating the pump-plunger, a cock controlling the supply of fluid to said motor and a connection between said cock and loaded gas-holder, substantially as described. 60

2. A double-acting gas and air compressing and mixing apparatus comprising a motor, a pump-plunger comprising a double cylinder, a water seal into which the double cylinder dips, means for admitting water automatically to the water seal, an open-ended cylinder dipping into a water seal carried by the double cylinder, a pump-cylinder A , air and gas pipes leading to the separated spaces formed by the double cylinder of the pump-plunger and the open-ended cylinder, a loaded gas-receiver surrounding the pump and means for controlling the water-supply connected with the said loaded receiver, substantially as described. 70 75

In witness whereof I have hereunto set my hand in presence of two witnesses.

JAMES KEITH.
